UNITED STATES PATENT OFFICE

CHARLES J. GIBBONS, OF BRIDGEPORT, CONNECTICUT

ROLLING MILL

Application filed August 3, 1927. Serial No. 210,317.

This invention relates to rolling mills and particularly to mills of the type which are known as four-high mills, that is employ two working rolls of relatively small diameter and 5 backed or supported by two backing rolls of relatively large diameter to take the strain from the smaller rolls. Rolls of this type have been found to be very efficient and capable of making large reductions with relatively 10 small expenditure of power, as well as uniformly rolling metal to a very thin gauge. Difficulty has been encountered with these rolls, however, in taking up the end thrust and preventing tendency of the small working rolls to shift longitudinally, because as the necks are necessarily of relatively small diameter as the rolls are small there is not sufficient room within the housing to mount 15 bearings which can properly absorb these end thrust forces and prevent the roll shifting.

It is, therefore, an object of my invention to provide means for effectively taking care of these end thrust forces and preventing 20 longitudinal shifting of the rolls.

It is also an object of the invention to provide an improved means for adjusting the drive for these rolls so that it may be placed in proper alignment with them as the rolls 25 are shifted for different gauges of metal, or where their centers are changed due to the use of different diameters of rolls.

With the foregoing and other objects in view, I have devised the construction illustrated in the accompanying drawings forming 30 a part of this specification. In these drawings,

Fig. 1 is a front elevation of a rolling mill involving my invention, a portion of the housing being broken away to illustrate the means for mounting the rolls, and a portion of the drive for one of the work rolls being shown in section.

Fig. 2 is an end elevation of a portion of the 45 drive broken away to more clearly show the construction.

Fig. 3 is a vertical detail section of the adjustable mounting for the main drive gear for each work roll.

Fig. 4 is a front elevation of the two work

rolls and their mountings with part of the driving mechanism in section, and showing in detail my improved means for preventing the rolls shifting endwise.

Fig. 5 is a detail section of one of the 55 bearings taken at right angles to the plane of Fig. 4, the section being substantially on line 5-5 of Fig. 4, and

Fig. 6 is a vertical detail section substantially on line 6-6 of Fig. 4.

The roll structure comprises a base or bed 10 on which the housings 11 are mounted. These housings have the usual upright slots or openings 12 in them for the bearings for the rolls and also for insertion and removal of the relatively small work rolls. In the present arrangement 13 are the relatively small work rolls located one above the other and each is backed up by a relatively large 15 backing roll 14. These backing rolls engage the work rolls and are of the required great strength to prevent undue flexing of the work rolls under the high pressure required in rolling operations. These rolls have suitable necks 15 at their opposite ends running in suitable bearing boxes 16 mounted in the 20 housings and which boxes for the upper rolls are movable vertically for adjustment of this roll as required for different thicknesses of metal and for different diameters of working rolls. This roll may be adjustable in the usual manner by adjusting screws 17 carried at the top of the housings and carrying the usual yoke 18 connected by supporting rods 25 19 to the lower section 20 of the boxes for purposes of adjusting the roll.

The work rolls 13 are of relatively small diameter, in practice ranging from one inch and a quarter to four inches in diameter, and it will, therefore, be seen that the necks 21 and 22 forming the bearings for these rolls are relatively close together and there is not a great deal of space available for bearings of the usual type which will properly absorb the end thrust of these rolls.

I have overcome this difficulty by the construction shown more in detail in Figs. 4 to 95 6. I mount on opposite sides of the opening or slot 12 in each housing upright bearing blocks or gibs 23 which are permanently se- 100

cured in place by means of bolts 24 passing through the housing and threaded into these blocks, as indicated at 25. On opposite sides of the necks of these small working rolls are vertically slideable bearings 26 and 27 which are usually made of brass or bronze. These bearings for the longer neck 21 or the neck at the driving end of the roll have laterally or radially extending flanges 28 engaging the outer edge of the bearing blocks 23, as shown particularly in Fig. 5, so as to form sufficient support for the bearing to take up any end thrust on these bearings tending to force them inwardly toward the roll. Between these bearings and the face of the blocks 23 are steel wear or shim plates 29 which are secured to the bearing blocks 26 by suitable screws 30. As the blocks or gibbs 23 wear or the bearings wear on the concave side next to the roll neck, this wear may be taken up by removing the old plates and substituting new plates of a greater thickness to correspond with the amount of wear. The shorter bearings 27 have similar wear plates 31, and if desired there may be a short end plate 32 at the short end of the roll fastened to the upright blocks 23 to prevent the bearings 27 moving longitudinally.

Outside the ends of the bearings 26 the neck of the roll is provided with a flange or rib 33 forming a shoulder 34 against which a shoulder formed on a collar 35 abuts, it being preferred to counterbore this collar, as shown in Fig. 4, to receive this flange. Thus the inner flat surface of this collar rests against and has a bearing on the outer ends of the bearings 26 and flanges 28. Outside this collar the roll neck is provided with a groove 36 in which is seated a ring 37 which is made in two sections so that they may be easily applied to the neck, and the sections are held in position in the groove by means of pins 38 passing through these ring sections and the neck of the roll. This ring butts up against the other side of the collar 35, and therefore, securely holds this collar in position against the shoulder 34. It also transfers thrust from the roll to the right, as viewed in Figs. 4 and 5, to the collar, which in turn transmits it to the ends of the bearings 26 which are held against longitudinal movement by the flanges 28 engaging the outer edges of the upright blocks 23. The thrust from the roll in the opposite direction or to the left, as viewed in Figs. 4 and 5, will be transmitted through the collar 35 through the shoulder 34. This thrust is transmitted by this collar directly to the hub 39 of the large driving gear 40 as the hub of this gear is set up against the outer surface of this collar. This hub is mounted to turn in the bearing 41 mounted in the bracket 42. The bearing 41 may be lined with suitable babbitt 43 or other suitable non-ferrous bearing metal, and the hub 39 has a flange

44 which bears against the inner end of the bearing and transmits the outward thrust from the collar 35 to the bearing which in turn transmits it to the bracket 42 through the flange 45. It will, therefore, be apparent that the collar 35 through its associated elements transmits the lateral thrust from the roll in either direction to suitable stationary elements and effectively prevents longitudinal movement of the roll so that it is always held in proper position. 75

The upper roll 13 is driven by a gear 46 at the opposite side of the housings, and this roll is held against longitudinal movement by the same construction as indicated at the right hand of Figs. 1 and 4. 80

The hub 39 of the large gears carries at its outer end a block 47 having a square opening to receive a square end of a spindle 48 which at its opposite end is square and is coupled through a coupling 49 to the square or wobbler end 50 of the roll neck, and through this connection the roll is driven from the gear. 85

It will be apparent from the foregoing that the bearings 26 and 27 are free to move vertically as the work rolls are adjusted for different thicknesses of material and to accommodate different diameters of rolls. It will also be obvious for best results the main driving gears 40 and 46 should be adjustable vertically so as to maintain their axes in substantial alignment with the axes of the rolls. For this purpose the brackets 42 carrying the bearings for these gears are secured to the housing so that they may be vertically adjusted. On the outside of each housing is a pair of aligned lugs 51 and 52 through which are passed the pivot bolts 53. The upper portion of this bolt is somewhat enlarged and threaded as shown at 54, to receive a nut 55. The bracket 42 is provided with a pair of bearing lugs 56 and 57. The upper bearing is recessed, as shown at 58, to receive this enlargement of the bolt while the lower bearing is recessed on the under side as shown at 59, to receive the threaded sleeve 60 which seats in a recess in the top of the lug 52. Threaded on this sleeve is an adjusting nut 61, and between this nut and the lower end of the bearing 57 is an end thrust ball bearing 62. It will thus be apparent that by loosening the upper nut 55 the bracket may be adjusted up or down by turning the nut 61, and then the upper nut may be tightened. The ball thrust bearing allows free swinging movements of the bracket 42 in and out. The free end of this bracket when in working position is secured to the housing by a block 63 through a clamping bolt 64 adapted to move vertically in a slot 65 in the housing and cooperating with the fork 66 on the bracket to clamp it to the housing. 110

The rolls in the construction shown are driven from a common shaft 67 mounted in 130

the base or bed 10. This shaft is driven through gears 68 from a shaft 69 driven by the motor 70, and the clutch 71 is used to cause driving connection between the driven gear 68 and the shaft 67 or to release this driving connection. The left hand gear 40 of the lower roll is driven from a pinion 72 on the shaft 67 through an idler 73. As the gear 40 is adjusted up and down to accommodate different sizes of rolls, the idler 73 is adjustable so that it may be moved to be always properly maintained in mesh with this gear. For this purpose this idler is mounted in a swinging yoke 74 which is mounted to swing about the axis of the shaft 67, so that as the gear 40 is moved up or down this idler can be swung out or in to lower or raise its position and maintain it always in mesh with the gear 40 and at the same time remain in mesh with the pinion 72. The yoke may have an arm 75 with a curved slot 76 in which there is a clamping bolt 77 to clamp this yoke in adjusted positions.

As the opposite gear 46 must rotate in the opposite direction to the gear 40, this gear is driven from a pinion 78 on the shaft 67 through two idlers 79 and 80. The idler 79 meshes with the pinion 78 and the second idler 80 meshes with the idler 79 and the gear 46. To always maintain this idler in mesh with the gear 46 as the gear is adjusted up and down this idler is mounted in a similar yoke 81 mounted to swing about the axis 82 of idler 79, and it has an arm 83 with a curved slot 84 and the clamping bolt 85 to secure it in adjusted positions, the same as the yoke 74.

Having thus set forth the nature of my invention, what I claim is:

1. In a rolling mill, a housing, a work roll having a bearing neck, a bearing for said neck mounted in the housing and held against longitudinal movement, a collar on the neck outside the housing secured against longitudinal movement thereon and engaging one end of the bearing, means supported outside the housing engaging the opposite side of the collar from the bearing to prevent movement of the roll in the opposite direction, and means for driving the roll.

2. In a rolling mill, a housing, a roll having a neck, a bearing for the neck in the housing held against movement longitudinally of the roll in one direction, means for driving the roll having a bearing outside the housing, means to prevent movement of the latter bearing longitudinally of the roll in the opposite direction from the direction against which the first bearing is held, a collar between said bearings and held thereby against lateral movements, and means to secure the collar to the roll neck to prevent relative longitudinal movement of the roll in the collar.

3. In a rolling mill, a housing, a roll having a bearing neck, bearings for said neck mounted in the housing, coacting means on

the bearings and the housing to prevent the bearings moving longitudinally toward the roll, a collar secured against longitudinal movement on the roll neck and engaging one end of the bearings, a driving means for the roll outside the housing including a bearing engaging the opposite side of the collar, and means to prevent longitudinal movement of the latter bearing away from the roll.

4. In a rolling mill, an upright housing having an opening therethrough, a work roll having a bearing neck in said housing, bearings for the neck in the housing, coacting means on the housing and the bearings to prevent movement of the bearing longitudinally toward the roll, a shoulder on the roll neck, a collar engaging the ends of the bearings and said shoulder, said neck also having a groove spaced from the shoulder, a ring in the groove and engaging the collar on the opposite sides thereof, said ring and shoulder acting to prevent longitudinal movement of the roll in the collar, and an abutment for the collar on the opposite side from the bearings.

5. In a rolling mill, a work roll having a bearing neck, a collar on said neck, means to prevent movement of the collar longitudinally of the neck in either direction, a stationary abutment for one side of the collar mounted in the housing, a support mounted outside the housing, and a stationary abutment for the opposite side of the collar carried by said support.

6. In a rolling mill, a work roll having a shoulder and a groove spaced from the shoulder, a ring secured in the groove, a collar secured between the ring and the shoulder, and stationary abutments for the collar on opposite sides thereof.

7. In a rolling mill, a work roll having a shoulder and a groove spaced from the shoulder, a ring secured in the groove comprising a plurality of sections, pins in the ring and roll to secure the ring sections in the groove, a collar secured against the shoulder by the ring and held against longitudinal movement on the roll by said ring and shoulder, and stationary abutments for the collar on opposite sides thereof.

8. In a rolling mill, a pair of upright housings, a pair of work rolls located one above the other, and having bearing necks, bearings for the necks in the housings held against lateral movement toward the rolls, a bracket secured to each housing, a driving gear for each roll mounted one in each bracket and having a bearing therein held against lateral movement away from the rolls, a collar on each roll engaging said bearings on its opposite sides, and means to secure the collars against longitudinal movement on their respective rolls in either direction.

9. In a rolling mill, an upright housing, a work roll having a bearing neck, bearings for

said neck in the housing, means to hold said bearings against movement toward the roll, a bracket secured to the housing, a driving gear for the roll having a bearing in the bracket held against movement away from the housing, a collar on the roll neck between said bearings, means to secure the collar to the roll neck to prevent longitudinal movement of the roll in the collar, and a driving connection for the gear to the roll.

10. In a rolling mill, a pair of upright housings, a working roll, bearings for said roll mounted for vertical movement in the housings, a bracket, a driving means for the roll having a bearing in the bracket, a mounting for the bracket to secure it to the housing and arranged to permit movement of the bracket toward and from the housing, and means for vertically adjusting the bracket.

15. In a rolling mill, a pair of upright housings, a working roll, bearings for said roll mounted for vertical movement in the housings, a bracket, an upright pivot bolt to pivot the bracket to the housing, means on 20 said bolt for adjusting the bracket up and down, a driving gear carried by the bracket, and a driving connection from said gear to the roll.

25. In a rolling mill, a pair of upright housings, a work roll between the housings, bearings for said roll mounted for vertical movements in the housings, vertically spaced lugs on one of the housings, a bracket, a bolt mounted in and extending between said lugs 30 and forming a pivotal support for the bracket, an adjusting nut carried by the bolt to adjust the bracket vertically, a driving gear carried by said bracket and having a bearing therein, and a driving connection from said 35 gear to the roll.

40. In a rolling mill, a pair of upright housings, a work roll between the housings, bearings for said roll mounted for vertical movements in the housings, a driving gear 45 for the roll, a driving connection from the gear to the roll, a support for the gear, means for mounting said support for vertical adjustment, a drive shaft, a driving gear on said shaft, an idler gear meshing with said 50 driving gears, a supporting yoke for said idler gear mounted to swing about said shaft as a pivot so that the idler may be kept in mesh with the gears after adjustment, and means for securing the yoke in adjusted 55 positions.

55. In a rolling mill, a pair of upright housings, a work roll between the housings, bearings for said roll mounted for vertical movements in the housings, a bracket secured 60 to one of the housings for vertical adjustment, a driving gear mounted in said bracket, a driving connection from the gear to the roll, a driving pinion, an idler gear meshing with said driving gear and said pinion, a yoke in 65 which the idler gear is mounted, said yoke

being mounted to swing about the axis of the pinion as a pivot to compensate for adjustment of the first mentioned gear, and means for securing the yoke in adjusted positions.

70. In a rolling mill, a housing, a roll having a bearing neck, bearings for said neck mounted for vertical adjustment in the housing, coacting means on the bearings and the housing to prevent the bearings moving longitudinally toward the roll, a collar mounted on the roll neck outside the housing and secured against longitudinal movement thereon, said collar engaging one end of the bearings, a driving means for the roll mounted 75 outside the housing including a bearing engaging the opposite side of the collar, and means to prevent longitudinal movement of the latter bearing away from the roll.

80. In a rolling mill, a pair of spaced 85 housings, a pair of work rolls arranged one above the other and having necks at their opposite ends, bearings for said necks in the housings, means for driving one of said rolls from one end, means for driving the other 90 roll from the opposite end, a collar secured against longitudinal movement on a neck of one roll, a collar secured against longitudinal movement on the opposite neck of the other roll, and means cooperating with said 95 collars to prevent longitudinal movement of the rolls.

In testimony whereof I affix my signature.
CHARLES J. GIBBONS.
